Primary Examiner — Kevin Keith Rudzinski*Assistant Examiner* — Jack Reickel(74) *Attorney, Agent, or Firm* — Dinsmore & Shohl LLP(57) **CLAIM**

The ornamental design for a display panel with a computer icon, as shown and described.

DESCRIPTION

The FIGURE is a front view of a display panel with a computer icon.

The broken elements in the FIGURE, depicting a display panel, are environmental elements, and form no part of my new design.
